FLOOR CONSTRUCTION

Allyn B. Rice, Los Angeles, Calif., assignor to A. B. Rice Floor Company, Los Angeles, Calif., a corporation of California

Application February 26, 1940, Serial No. 320,801

7 Claims. (Cl. 20—8)

This invention relates generally to flooring, and more particularly to portable floors.

An object of the invention is to provide a portable floor characterized by sections or panels capable of being easily assembled and disassembled; which is adapted to any type of under construction, such as concrete, turf, sand or joists; which raises the floor level a minimum amount, as is an important advantage in installations having limited door height and ceiling clearances; and which has a beautiful finished and jointless appearance comparable to a high quality permanent floor of the pattern type.

Another object of the invention is to provide a portable floor of the above described general character in which the floor sections are built up in a manner to be extremely rigid, and yet are of a minimum thickness so as to minimize weight and thus facilitate handling of the sections, as well as reduce transportation costs.

A further object of the invention is to provide a portable floor in which the floor sections are constructed with a novel detachable connection insuring and maintaining an absolutely accurate joint between sections which is unaffected by temperature changes, and which is undetectable from joints in parts of the floor section forming a predetermined pattern thereon, whereby the floor will have the finished appearance of a permanent installation.

With these and other objects in view, the invention resides in the combinations, arrangements and functional relationships of elements set forth in the following specification and particularly pointed out in the appended claims.

In the accompanying drawing,

Figure 1 is a plan view of a number of floor sections assembled to form the floor embodying this invention;

Figure 2 is a top plan view of a typical floor section;

Figure 3 is a bottom plan view of the floor section;

Figure 4 is an enlarged fragmentary sectional view taken on the line 4—4 of Figure 1 to illustrate the novel joint construction between floor sections;

Figure 5 is a vertical sectional view of the floor in its association with a modified form of foundation.

Referring specifically to the drawing, the portable floor is composed of rectangular sections F which preferably have a length twice their width or have the same length as width in order to form staggered joints J and J', as shown in Figure 1.

it being understood that in practice these joints are undetectable and cannot be distinguished from the individual pieces making up a parquet or other continuous pattern throughout the area of the floor.

Each floor section F comprises a sub-floor or base panel 10, preferably constructed of plywood, on which is secured by nails or other fastening means, the pieces 12 making up the parquet design and forming the finish panel 13. For the purpose of illustration, a simple design of alternating longitudinal and transverse rectangularly shaped tongue-and-groove pieces laid in rows to form squares, is illustrated, but it will be understood that any other suitable design can be employed instead.

A thin layer of floor mastic 14 or similar substance is first applied to the base panel 10 and the pieces secured to the base panel by nails 16 driven into the latter and by screws 16 driven from the base panel into the pieces 12 around the edges of the floor section as shown in Figure 3.

This operation is most easily performed in a suitable jig (not shown) which relates the finish panel and base panel so that one longitudinal edge and one transverse edge of the latter project beyond the corresponding edges of the finish panel 13, as indicated at 17, and the other longitudinal and transverse edges of the finish panel complementarily project beyond the corresponding edges of the base panel 10 as indicated at 18. Thus, when the floor sections are assembled, as shown in Figures 1 and 4, the finish panels 13 of the sections overlap the base panels of adjacent floor sections, with the edges of the finish panels tightly abutting when the edges of the base panels are clear of each other as shown at 19 in Figure 4, so as to insure that the finish panels can be brought into abutting relation.

The vertical edges of those pieces 12 which form the longitudinal and transverse edges of the finish panels 13 are provided with grooves 20 which receive metal splines 21 permanently seated in the grooves of those longitudinal and transverse edges of the panels 13 beyond which project the corresponding edges of the base panels.

Thus, one longitudinal edge and one transverse edge of each floor section carries a spline 21 which is tightly and detachably received in the groove of the abutting edge of the next section when the sections are assembled. The splines 20 positively prevent any misalignment of the sections at the joints therebetween and insure that there can be no relative vertical displace-

ment between the sections when the floor is in service and is subjected to variable and/or moving loads.

In an installation utilizing an under construction composed of joists 25 resting on a solid foundation such as a concrete floor or solid ground, the joists are first arranged in parallelism at predetermined distances apart with certain joists disposed to support the edges of abutting floor sections as shown in Figures 1 and 4, so as to enable the floor sections to be secured to the joists by wood screws 26 driven through the projecting portions 17 of the base panels 10 of the sections into the joists in the manner shown in Figure 4.

In the event that joists are not desirable, the floor sections can be assembled on kiln dried sand 27 which is screeded and leveled on any suitable solid foundation 28. In this event, it is necessary that the floor be surrounded by walls 29 of a room or by a suitable frame on the ground so as to enable the sections to be confined against separation by suitable wedges 30 or other means between the edges of the border sections and the room walls or enclosing frame.

With either construction, it will be manifest that the portable flooring embodying this invention provides for a minimum loss of headroom in a building by the relatively thin and structurally strong built-up floor sections co-acting by means of the novel construction between sections to form a smooth continuous patterned floor surface in which the joints between sections are undistinguishable from the joints between pieces composing the pattern so that the floor will have the appearance of a high quality permanent installation.

Furthermore, the floor can be easily disassembled, and its individual sections salvaged or re-arranged to distribute the wear over all sections in installations in which traffic is heavier on one portion of the floor than on another, thus greatly increasing the useful life of the floor.

What is claimed is:

1. A portable floor comprising a plurality of floor sections each composed of a base panel and a finish panel provided with parquetry patterns, the base panel having certain edges projecting beyond the corresponding edges of the finish panel, the latter of which has other edges projecting beyond the corresponding edges of the base panel to provide a lap joint between the base and finish panels of confronting sections, and a butt joint between the finish panels thereof which is undistinguishable from the joints between the pieces of the parquetry patterns, whereby the sections will have the appearance of a continuous patterned floor; and means co-acting with the edge portions of confronting finish panels to detachably connect them against relative lateral displacement.

2. A portable floor comprising a plurality of floor sections each composed of a base panel and a finish panel provided with parquetry patterns, the base panel having certain edges projecting beyond the corresponding edges of the finish panel, the latter of which has other edges projecting beyond the corresponding edges of the base panel to provide a lap joint between the base and finish panels of confronting sections, and a butt joint between the finish panels thereof which is indistinguishable from the joints between the pieces of the parquetry patterns, whereby the sections will have the appearance of 75

a continuous patterned floor; the edges of the finish panels having co-incident mating grooves; and splines in said grooves co-acting therewith to detachably connect the floor sections against relative lateral displacement.

3. A portable floor comprising a plurality of floor sections each composed of a base panel and a finish panel provided with parquetry patterns, the base panel having certain edges projecting beyond the corresponding edges of the finish panel, the latter of which has other edges projecting beyond the corresponding edges of the base panel to provide a lap joint between the base and finish panels of confronting sections, and a butt joint between the finish panels thereof which is indistinguishable from the joints between the pieces of the parquetry patterns, whereby the sections will have the appearance of a continuous patterned floor; means co-acting with the edge portions of confronting finish panels to detachably connect them against relative lateral displacement; joists providing an under construction supporting the floor sections and being spaced so that certain joists support the edge portions of the sections; and fastening members extending through said projecting edges of the base panels and into the joists to secure the floor sections thereto.

4. A portable floor comprising a plurality of floor sections each composed of a base panel and a finish panel provided with parquetry patterns, the base panel having certain edges projecting beyond the corresponding edges of the finish panel, the latter of which has other edges projecting beyond the corresponding edges of the base panel to provide a lap joint between the base and finish panels of confronting sections, and a butt joint between the finish panels thereof which is indistinguishable from the joints between the pieces of the parquetry patterns, whereby the sections will have the appearance of a continuous patterned floor; means co-acting with the edge portions of confronting finish panels to detachably connect them against relative lateral displacement; a layer of kiln-dried sand on which the floor sections are laid within an area bounded by walls; and members co-acting with the edges of the border floor sections and adapted to co-act with the boundary walls in confining the sections against separation at their joints.

5. A portable floor comprising a plurality of rectangular floor sections each composed of a base panel and a parquetry patterned finish panel, the base panel having a longitudinal edge and a transverse edge projecting beyond the corresponding edges of the finish panel, the latter of which has its other two edges projecting beyond the corresponding edges of the base panel to provide a lap joint between the base and finish panels of confronting sections, and a butt joint between the finish panels thereof which is indistinguishable from the joints between the pieces of the parquetry patterns, whereby the sections will have the appearance of a continuous patterned floor; and means for confining the sections against separation at the joints thereof.

6. In a portable floor, a floor section comprising a rectangular base panel; a rectangular finish panel composed of pieces arranged in a parquetry design; means for securing the pieces to the base panel in parquetry formation and including fastening members extending through the base panel into those pieces forming the outer edge of the finish panel; the finish panel

being secured to the base panel with two adjacent edges of the latter projecting beyond the corresponding edges of the finish panel, and with the other two edges of the latter projecting beyond the corresponding edges of the finish panel to provide for a combination lap and butt joint between floor sections when assembled; the edges of the finish panel having grooves therein; and splines in the grooves of certain edges projecting from the grooves for co-action with grooves of other floor sections when assembled.

7. In a portable floor, a floor section comprising a rectangular base panel; a rectangular

5 finish panel; means securing the finish panel to the base panel with two adjacent edges of the latter projecting beyond the corresponding edges of the finish panel, and with the other two edges of the latter projecting beyond the corresponding edges of the finish panel to provide for a combination lap and butt joint between floor sections when assembled; the outer edges 10 of the finish panel having grooves adapted to receive splines to connect the floor section to others having such grooves in the edges thereof.
